United States Patent Office

Des. 183,953
Patented Nov. 18, 1958

183,953

ICE BUCKET OR SIMILAR ARTICLE

Joseph B. Stier, New York, N. Y.

Application April 7, 1958, Serial No. 50,345

Term of patent 7 years

(Cl. D58—17)

Fig. 1.

Fig. 2.

Fig. 3.

The rear and side, not shown, are substantially the same as the front and side, respectively, shown.

I claim:

The ornamental design for an ice bucket or similar article, substantially as shown and described.
